UNITED STATES PATENT OFFICE.

VINCENT THORPE, OF FALL RIVER, MASSACHUSETTS.

SHUTTLE-BINDER FOR LOOMS.

SPECIFICATION forming part of Letters Patent No. 475,069, dated May 17, 1892.

Application filed July 23, 1891. Serial No. 400,480. (No model.)

To all whom it may concern:

Be it known that I, VINCENT THORPE, of Fall River, in the county of Bristol and State of Massachusetts, have invented certain new and useful Improvements in Shuttle-Binders; and I hereby declare that the following is a full, clear, and exact description of the same, reference being had to the accompanying drawings, forming part of this specification.

10 This invention relates to improvements in the construction of shuttle-binders used for binding shuttles in the boxes of looms.

The object of the invention is to produce a new and more durable shuttle-binder which 15 can be more readily adjusted than those heretofore used.

To this end my invention consists in the peculiar features of construction and combination of novel parts which will be more fully 20 described hereinafter, and pointed out in the claim.

Figure 1 is a front view of a portion of a shuttle-box, showing the shuttle-swell of the improved binder. Fig. 2 is a top view of the 25 same, the shuttle-guard being broken away. Fig. 3 is a cross-sectional view of the same, taken at line *a b*, Fig. 2.

Similar numbers of reference designate corresponding parts throughout.

30 In the drawings, 5 indicates the shuttle-swell, which is slightly bowed in shape and extends part way through the opening 6 in the back 7 of the shuttle-box, the rear end of the swell being shaped to extend farther into 35 the box than the forward, thus presenting a sloping surface to the travel of the shuttle. The slotted stops 8 8 form the upper ends of the curved swell-fingers 9 9, which extend downward and are curved inward, finally 40 uniting in the sleeve 10, provided with set-screws 11 11, by which the sleeve is secured in place on the rock-shaft 12. The ends of the bowed piece 5 forming the swells are secured to these slotted stops 8 8 by bolts which, 45 being adjustable in the slots, can be raised or lowered and thus adjust the location of the

swell 5 to any possible variation in the height of the opening 6, while the extension of such swell through the opening 6 may be regulated by washers placed on said bolts between the 50 end surfaces of the swell, to which the bolts are secured, and the striking-surfaces of these slotted stops.

The rock-shaft 12 is of the usual construction, except that the end is not bent at right 55 angles with the main portion to engage the sleeve of the swell-finger, but is continued in a line with the main portion, as is shown in the drawings. This rock-shaft is secured in bearings in the ordinary manner and is operated or rocked by a shuttle entering the shuttle-box and striking the swell 5, forcing this swell outward and also forcing outward the slotted stops or upper ends of the swell-fingers, which, forming part of the sleeve 10 secured to said rock-shaft, tend to turn or rock 60 the same and raise the dagger carried or operated thereby to a position to allow the lay to beat up. By the construction thus described I am able to produce a shuttle-binder 65 which can be adjusted to bring more or less pressure against the shuttle, the cost of manufacture will be reduced, and operation will be 70 more perfect.

Having thus described my invention, I 75 claim as new and desire to secure by Letters Patent—

The combination, with the rock-shaft 12 of a loom, of a sleeve 10, provided with securing-screws 11 11, the upwardly-extending 80 swell-fingers 9 9, formed integral with said sleeve, the slotted stops 8 8, forming the upper ends of said fingers, and a swell 5, adjustably secured at its ends by bolts to the slotted stops 8 8 and extending through the opening 85 6 into the shuttle-box, as and for the purpose described.

VINCENT THORPE.
